FIRE WALL

Michael Liptak, St. Paul, Minn.

Application January 10, 1931, Serial No. 507,845

9 Claims. (Cl. 72—101)

This invention relates to improvements in fire walls, and is particularly concerned with means for connecting replaceable facings of such walls, in such manner that the connecting means, as well as the wall or brick elements of the facing or replaceable wall, can be replaced or repaired without disturbing any portion of the permanent wall. Among the objects are to provide wall elements adapted to receive metal connectors, the connectors and wall elements or bricks being so constructed that the connectors may be dropped into position as the wall is built, and when so dropped automatically assume such relation as will prevent separation of the wall but will permit limited motions of the replaceable wall (due to expansion and contraction by heat) lengthwise, transversely and vertically. Another object is to provide connectors having abutments cooperable with the wall or walls in such manner that each connector can only be disengaged after rotative motion, and therefore cannot become accidentally disengaged, as the result of expansion movements of the wall or walls.

The important ideas of means of the present invention are: the arrangement whereby the connectors can be removed from the permanent wall without dismantling the wall; the use of connecting means which cannot possibly be accidentally disengaged by expansion motion of the wall or walls; the use of a shouldered socket in which the shoulder extends clear to the top of the block (or is of sufficient height) so that no vertical motion of the walls can tip any connector and cause it to be disengaged from its shouldered socket, but so that the connector can move vertically conformably to replaceable wall motions under action of heat; the formation of the replaceable wall substantially entirely by elements arranged as headers; the production of shouldered sockets by means of two complementary bricks of a configuration which lends itself to machine production, all bricks being identically similar; and the formation of shoulder-providing sockets to allow lateral motions of the connectors conformably to longitudinal expansion motions of the replaceable wall.

Features include all details of construction, as well as the broader ideas of means disclosed.

Features and advantages will be pointed out in the description of the drawings forming a part of this application and in said drawings.

Figure 1 is a sectional perspective view illustrating a hollow fire wall constructed in accordance with the teachings of this invention, and using two-piece, shoulder-providing elements;

Figure 2 is a sectional perspective view illustrating a solid fire wall constructed in accordance with the teachings of this invention, and using one-piece, shoulder-providing elements;

Figure 3 is a plan view illustrating the important feature of this invention, to-wit: the drop-in connector, and its relation to the shoulder-providing wall elements;

Figure 4 is a vertical section showing the connector ready to be withdrawn, and after having been rotated through an angle of 90° from its position shown in Figure 3 to disengage its abutments from the socket shoulders; and

Figure 5 is a plan view of a modification.

The present device provides a fire wall constructed of permanent and replaceable portions, each having bricks therein providing shoulders, and connectors are provided having abutments engaging shoulders of corresponding wall elements in a manner to prevent transverse separation of the walls.

Referring first to Figure 1: Numeral 1 generally indicates the permanent wall of a fire wall structure, and numeral 2 generally indicates the replaceable wall or facing or lining. The permanent wall in this instance is formed from common brick 3, laid as stretchers, and with courses of fire brick laid as headers and including elements 4 and pairs of bricks indicated at 5. Courses of elements 4 and 5 are provided at different levels as shown, and the elements 5 provide shouldered sockets, in this instance, T-shaped in plan view. The shoulders extend the full height or thickness of the blocks, and the stretcher courses above and below cap the vertical slots 30 or T-shaped or shouldered sockets. Elements 5 are arranged in pairs as shown in Figure 1, and each is notched at one corner as shown, and the notches are opposed to provide a shouldered socket, in this instance T-shaped, providing a throat 40, opening on the vertical side, and leading inwardly to a cross passage 9, which is wider than the throat, and extends therebeyond to form shoulders 12. The throat extends in a direction which corresponds to the transverse dimension of the wall. The throat 8 is preferably flared outwardly as at 13. All blocks, whether of the solid type shown in Figure 3 or of the sectional type shown in Figure 1, are identical and are reversible, and this is an important feature of the invention. This sectional, or two brick shoulder-providing structure, can be made at about half the cost of the whole brick or block structure indicated at 20, in Figure 3, for the principal reason that the corner notching can be accomplished by machine 55.

moulding, while the whole block must be hand moulded. The machine-made brick is of a quality superior to the hand-made brick, in that the brick is less likely to sprawl, and the half bricks 5 can be handled with one hand, and, therefore, the wall can be constructed more rapidly.

Whether the shoulder-providing elements are one or two-piece in construction, a shoulder is provided with which one of the abutments of a connector can be engaged to resist separation of the walls with which the device is associated. In 10 this instance the connectors are I-shaped, and include abutments 16, one at each end of shank 17. The depth C of the shoulders and socket is 15 in all instances greater than the length E of the abutment, so that on turning the I-shaped connector through an angle of 90° from its horizontal flat position shown in Figure 3, the connector can be withdrawn from the socket in direction 20 of the arrow F. This withdrawal can, therefore, be made without dismantling any portion of the permanent wall 1, and can only be made after a rotative motion sufficient to disengage the abutment 16 from the shoulder 12. 25 Elements 5 and/or 20 are also arranged in the replaceable wall 2 in substantially the same manner as the arrangement in permanent wall 1, see Figures 1 and 2. Between the courses of elements 5 and 20 are laid courses of header elements 7. 30 The abutments 16 of the connectors respectively engage corresponding shouldered sockets in the walls, to secure the replaceable wall to the permanent wall.

The flared throat 8 permits some play of the 35 shank 17 in the throat conformably to expansion motions of the replaceable wall lengthwise. It will be noted that the shoulder does not extend from the top face of the block to the bottom of the socket, in the construction shown in Figures 2, 40 3 and 4, but that this shoulder does extend the full height or thickness of the block in the construction shown in Figure 1. The point is that downward motion of the replaceable wall is allowed to some extent with no possibility of the 45 connector becoming disengaged. In other words, it can move in a vertical plane, but can only be disengaged when turned through substantially an angle of 90°.

Referring now more particularly to the arrangement of the shoulder-providing elements in 50 the walls: It will be noted that the shoulder blocks are separated by pairs of key or spacing bricks. In the form shown in Figure 1, wherein two bricks are employed and arranged in complementary relation to provide the shouldered socket, the two interposed key bricks act not only to prevent separation of the socket-forming bricks, but at the same time when it is desired to dismantle the wall, these bricks can be removed and when so 55 removed release one or more of the complementary socket-forming elements, so that they may be moved laterally away from the abutment 16. When the key bricks of Figure 2 are removed, the socket-forming elements are also conditioned 60 to be removed, but in this case to remove the socket-forming element 20, it must be raised or lowered to disengage it from the abutment of the connector. The construction of Figure 1, therefore, has the advantage of disconnection of the 65 socket-forming bricks from the connectors by horizontal rather than vertical motion. In all instances, the socket-forming elements are, for their particular types, identical so that they may be used in either wall. This is an important feature because all bricks have the same form, and 70

are reversible. In the construction of Figure 2, of course, the bricks must be laid so as to have their sockets facing upwardly, because in this instance the socket does not extend entirely through the brick. However, in the form shown in Figure 1, the socket extends clear through the brick, or the shoulder and socket-forming notches in the bricks, extend the full height or thickness of the brick. Of course, the sockets of bricks 20 could extend all the way through.

In Figure 2, those vertical faces of the sockets and shoulder-providing elements, which are flush with that surface of the replaceable wall which is exposed to the heat, have been stippled to more clearly indicate their positions. In Figure 1, the 15 same surfaces of the complementary pairs of socket-forming bricks have been similarly stippled.

Another feature of the invention is that both the permanent and replaceable walls are built from standard brick, or from brick all of the 20 same dimensions, and particularly of the same vertical thickness. The dimensions of the standard brick are 2 1/2 x 4 1/2 x 9 inches. Another feature is that the permanent wall is constructed by bricks, all of which are standard size, some 25 of which may be common brick and others refractory brick. It is true that in both forms of the invention the socket-forming bricks are special bricks, but the vertical thickness is the same as the other bricks in the wall, and the 30 dimensions are standard, so that the bricklayer has to make no calculations other than the ordinary calculations in building the wall. In other words, he does not, as in my copending application for Fire walls, Serial Number 396,184, have 35 to lay bricks in a special manner because of the increased thickness of the special-dimensioned elements indicated in the drawing of that case by the numeral 3.

Another feature of the invention is illustrated 40 in Figure 5. This practice has materially reduced the amount of special brick. I use half bricks 5^a, laid as shown and each provided with an L-shaped socket. These bricks are identical with the bricks 5. Each provides a shoulder 12^a, and the 45 L-shaped sockets are closed on one side by common or fire brick 25, the opposite sides of which bricks also function to close or complete the sockets in the next pair of bricks 5^a. By this means, only one-half as many bricks 5^a are necessary. The 50 connectors 17^a in this case are not I-shaped but half-I-shaped in plan. In this case, also, the connectors can be removed after rotation, without dismantling the permanent wall. The wall sections 1^a, 2^a, can be spaced as in Figure 1, or 55 be abutted as in Figure 2.

Another feature of the invention is that by the practice of this invention, the permanent wall can be partly built of standard common brick, as distinguished from standard fire brick, and this brick can be laid in mortar and then the replaceable wall can be built of standard fire brick laid in fire clay cement. This fire clay cement is applied in very thin layers, as distinguished from the very much thicker layers of 60 mortar used with common brick. In the drawings, this layer of fire clay cement has not been shown because, as a matter of fact, it is somewhat film-like.

It is again to be noted, and this is a feature, 70 that only one type of special brick is required for providing the shouldered socket. Nevertheless, there is no intention to be limited to a special brick because it is conceivable that fire brick can be so laid as to provide a shouldered socket with 75

which a connector can be engaged, first by inserting and then by rotating. Both walls can be built by using only special bricks 20 or only by using special bricks 5, the latter brick being one-half the size of the former. It is again to be noted that the special bricks 20 and 5 are all of the same thickness, and they are of the same thickness as the other fire brick, that is the thickness of a standard fire brick which is two and one-half inches.

I claim as my invention:

1. Permanent and replaceable walls each having bricks arranged therein to provide sockets having shoulders which extend longitudinally of the wall, and connectors having abutments engaging corresponding shoulders of the wall in a manner to prevent transverse separation, the sockets, shoulders and abutments being so related that the abutments can be released from the shoulders only after a rotative movement of the connectors to permit free withdrawal of the connectors from the permanent wall, the sockets being faced upwardly so that the connectors can be dropped into connecting position as the wall is built, and said connectors being held in operative position by the action of gravity.

2. A wall having permanent and replaceable portions, bricks in both walls some bricks of which provide horizontal sockets and shoulders, connectors arranged in the sockets and having abutments engaged with the corresponding shoulders to prevent transverse motion of the bricks, said sockets, shoulders and abutments being so formed that the connectors can be rotated and can, after rotative motion, have their abutments disengaged from the shoulders and can be withdrawn from the sockets without dismantling any portion of the wall, some of the sockets and shoulders being formed by two complementary bricks.

3. Permanent and replaceable walls each having bricks providing shoulders, and connectors having abutments engaging corresponding shoulders of the walls in a manner to prevent transverse separation of the walls, the shoulders being of sufficient vertical height to permit vertical motions of the connectors, as the replaceable wall correspondingly moves under the action of heat, and the shoulders and abutments of the permanent wall being so related that the connectors can be rotated and can, after rotative motion, be freely withdrawn, said sockets being formed to allow lateral motions of the connectors conformably to longitudinal expansion motions of the replaceable wall.

4. In a fire wall structure, permanent and replaceable walls, the permanent wall having shoulders extending longitudinally thereof, connectors having means engaging the shoulders in a manner to normally prevent transverse withdrawal of the connectors from the wall, and said connectors being anchored in the replaceable wall, the shoulders and shoulder-engaging means being so related that the connectors can be rotated, and can only after a predetermined degree of rotative motion be released for withdrawal in a horizontal direction without dismantling any portion of the permanent wall.

5. A permanent wall comprising bricks having

vertical T-shaped sockets therein which open on the inner side of the wall, horizontal connectors having T-shaped terminals each connector comprising a head and shank, the heads being abuttingly engaged in corresponding T-shaped sockets in a manner to prevent horizontal withdrawal from the sockets when the long axes of the heads are substantially horizontally disposed, the depths of the sockets and the lengths of the heads being such that any connector can be rotated to dispose the long axes of its head in substantially vertical position, whereafter said connectors can be withdrawn from the socket, and a replaceable wall of fire brick with which the opposite ends of the connectors are engaged in a manner to prevent separation of said replaceable wall from said permanent wall.

6. A permanent wall and a replaceable wall each comprising bricks, each of some of the bricks having a vertical T-shaped socket therein opening at the top and at the inner side of the brick, I-shaped horizontal connectors each comprising a shank and a head, the heads being abuttingly engaged with the corresponding T-shaped sockets to prevent horizontal withdrawal and transverse separation of the walls when the long axes of the heads are horizontally disposed, the depth of the sockets and the lengths of the heads being such that the connectors can be rotated to dispose the long axes in a vertical direction, whereafter the connectors can be withdrawn.

7. A wall having permanent and replaceable portions, bricks in both walls some of which provide sockets and shoulders into which connectors can be dropped during building of the wall, connectors arranged in the sockets and having abutments engaged with corresponding shoulders to prevent transverse motion of the bricks of the replaceable wall, each socket and its shoulder being formed by parts of two bricks, which are disposed in the same horizontal plane.

8. In a brick fire wall structure, a permanent wall, a replaceable wall, links connecting certain corresponding bricks of respective walls to prevent transverse separation, and plural means provided respectively by said permanent wall and links cooperative to permit rotation of any link in the permanent wall, and only after a predetermined degree of rotation to permit horizontal withdrawal of any link without dismantling any portion of the permanent wall.

9. A permanent wall comprising bricks having sockets therein which open on the inner side of the wall, horizontal connectors, each connector comprising a head and a shank, the heads being abuttingly engaged in corresponding sockets in a manner to prevent horizontal withdrawal from the sockets when the heads are in their normal position, the dimensions of the sockets and heads being such that any connector can be rotated to disengage its head from its shoulder, whereafter the connector can be withdrawn from the socket in a horizontal direction, and a replaceable wall of fire brick with which the opposite ends of the connectors are engaged in a manner to prevent separation of the replaceable wall from the permanent wall.

MICHAEL LIPTAK.
